COMBINATION KEY RING AND TAPE MEASURE

Robert A. Bennett, Lot 6, Palmouth Drive, Huntington,
Conn. 06484, and John Peterson, Jr., Long Meadow
Road, Orange, Conn. 06477

Filed Nov. 6, 1967, Ser. No. 9,282

Term of patent 14 years

(Cl. D50—4)

FIG. 1

FIG. 2

FIG. 3

FIG. 4

FIG. 5 FIG. 6

FIGURE 1 is a perspective view of the combination key ring and tape measure.

FIGURE 2 is an elevational view of one side of the combination key ring and tape measure, the other side being the same.

FIGURE 3 is a top plan view;

FIGURE 4 is a bottom plan view;

FIGURE 5 is an elevational view of one end of the tape measure; and

FIGURE 6 is an elevational view of the other end.

We claim:

The ornamental design for a combination key ring and tape measure, as shown and described.
